UNITED STATES PATENT OFFICE.

JOSEPH EMILE TÉTU, OF LEWISTON, AND WILLIE E. CUTLER, DECEASED, LATE OF AUBURN, MAINE, BY EMMA E. CUTLER, ADMINISTRATRIX, OF AUBURN, MAINE, ASSIGNORS TO DRAPER CORPORATION, OF HOPEDALE, MASSACHUSETTS, A CORPORATION OF MAINE.

BEAM-LOCK FOR LOOMS.

1,233,282.

Specification of Letters Patent. Patented July 10, 1917.

Application filed January 29, 1917. Serial No. 145,275.

To all whom it may concern:

Be it known that JOSEPH E. TÉTU, a subject of the King of Great Britain, residing at Lewiston, county of Androscoggin, State 5 of Maine, and WILLIE E. CUTLER, deceased, late of Auburn, county of Androscoggin, State of Maine, did invent an Improvement in Beam-Locks for Looms, of which the following description, in connection with the 10 accompanying drawing, is a specification, like characters on the drawing representing like parts.

This invention relates to looms and is particularly concerned with the device 15 known as the beam lock by which the journals of the warp beam are held in their bearings in the side frames of the loom.

The object of the invention is to provide a simple and efficient beam lock of an adjustable character by which adjustment may be provided to take up wear and insure that the warp beam shall rotate smoothly and evenly.

In the operation of the loom considerable 25 wear is caused on the journals of the warp beam and on the bearing of these journals in the said frames. This causes jumping or vibration of the heavy warp beam particularly when the beat up takes place. This is 30 highly undesirable because of its effect upon the tension of the warp and consequently upon the cloth being woven. The present invention provides for taking up any wear of this sort and thus eliminates this difficulty.

The invention also has for its object to provide a self-contained adjustable beam lock of a symmetrical nature which may be attached to either side of the loom.

These and other features of the invention 40 will appear more fully from the accompanying description and drawings and will be particularly pointed out in the claims.

The drawings illustrate so much of a loom 45 as is necessary to an understanding of the invention together with a preferred form of the invention embodied therein.

In the drawings,

Figure 1 is a front elevation of one side 50 frame of a loom and portion of a warp beam

together with a beam lock embodying a preferred form of this invention;

Fig. 2 is a side elevation of the construction shown in Fig. 1;

Fig. 3 is a detail much enlarged of a portion of the construction including the beam lock as shown in Fig. 2 with one of the side plates of the beam lock removed.

One end of a warp beam 1 with its journal 2 resting in an open bearing 3 in the side frame 4 is sufficient to illustrate the invention because the opposite end of the warp beam, the opposite journal, and the opposite side frame are all of similar and well known construction.

The shoulder of the side frame in which is formed the bearing 3 is also shown as provided adjacent the bearing 3 with a recess 5 which may be the recess upon which the journal 2 of the warp beam is ordinarily 60 rested in the operation of placing a warp beam in position in its bearings. The beam lock illustrated as a preferred form of this invention comprises a body section and a bearing section 6 movably mounted on the 65 body section. In the construction illustrated the body section is formed of a casting 7 of the general shape shown and two side plates 8 secured to and at each side of the casting 7 by rivets 9. These side plates 70 are shorter than the casting 7 which projects upwardly at 10 above the side plates. The bearing member 6 is shaped at its upper end to provide a recess 11 to fit over the journal 2 of the warp beam and is pivotally 75 mounted in the side plates as by a rivet 12 so that it may move or swing toward and from the upstanding portion 10 of the casting 5 of the body section.

A set screw 13 is threaded through the 80 upstanding portion 10 of the body section and abuts at its end against the back of the bearing section 6. This set screw is provided with a lock nut 14. It will thus be seen that by adjusting the set screw 13 the 85 position of the bearing section 6 with respect to the body section is adjusted and that by setting up the lock nut 14 this adjustment of the bearing section is retained.

Suitable means are provided for securing 90

the body section and consequently the adjustable beam lock rigidly to the side frame adjacent to the open bearing for the warp beam journal. In the construction illustrated the body section is provided with an elongated aperture 15 extending transversely therethrough and consequently through both side plates and the intermediate casting. A set screw 16 is secured in the side frame 4 in an appropriate position with respect to the warp beam journal bearing and is provided with a thumb nut 17 and a lock nut 18. The body section of the beam lock at the upstanding end 10 of the casting is provided at both sides with laterally projecting symmetrically arranged hubs 19 so positioned that when the aperture 15 is over the set screw 16 one of these hubs rests in the recess 5 of the frame. The aperture 15 is of such a size as to allow the hub 19 to seat in the recess 5 under slightly varying conditions.

When the beam lock has been placed in position on the loom side the thumb nut 17 is turned up and the lock nut 18 set so that the body section of the beam lock is rigidly secured to the side frame.

In the use of the device the beam lock is removed from the side frame, the warp beam 30 is placed in position with its journals 2 resting in the bearing 3, the beam lock is returned to position on the side frame with the hub 19 resting in the recess 5, and the aperture 15 over the set screws 16, and with the recess 11 of the bearing section in contact with the journal 2 or as close to it as possible. The thumb nut 17 and lock nut 18 are then set up tight and then the set screw 13 adjusted to bring the bearing recess 11 in contact with the journal 2 and the lock nut 14 set up.

The journal of the warp beam will thus be held snugly and properly in its bearing. When any wear takes place the set screw 13 45 is adjusted to re-adjust the bearing section 6 thus maintaining the bearing snug and in proper condition at all times.

The construction is precisely the same at each side of the loom and as the bearing section 50 6 is journaled centrally of the body section and the hubs 19 are provided at each side the lock nut is a symmetrical structure and the same structure is employed at each side of the loom.

55 Having thus fully described our invention, what we claim as new and desire to secure by Letters Patent is:

1. In a loom having a warp beam and side frames provided with open alined bearings 60 to receive the warp beam journals, an adjustable beam lock for each side frame comprising a body section, a bearing section movably mounted on said body section, means for securing the body section rigidly 65 to the side frame adjacent its open bearing

and means for adjusting and retaining in adjusted position the bearing section with respect to the body section.

2. In a loom having a warp beam and side frames provided with open alined bearings 70 to receive the warp beam journals and with recesses adjacent said bearings, an adjustable beam lock for each side frame comprising a body section, a bearing section movably mounted on said body section, a hub 75 projecting from the side of the beam lock and adapted to rest in one of said recesses, means for securing the body section to the side frame with its hub resting in the recess of the side frame and with the bearing 80 section adjacent the open bearing whereby the body section is held rigidly to the side frame, and means for adjusting and retaining in adjusted position the bearing section with respect to the body section.

3. In a loom having a warp beam and side frames provided with open alined bearings 85 to receive the warp beam journals, an adjustable beam lock for each side frame comprising a body section, a bearing section 90 pivotally mounted in said body section, means for securing the body section rigidly to the side frame adjacent its open bearing, a set screw threaded into the body section and abutting the bearing section whereby the bearing section may be adjusted with respect to the body section.

4. An adjustable beam lock for looms comprising a body section, a bearing section pivotally mounted in the body section, a set 100 screw threaded into the body section and abutting the bearing section, the said body section being provided with a transverse aperture through which securing means may be passed and a hub projecting from the 105 side of said body section and adapted to co-operate with a recess in the side frame of the loom.

5. A symmetrical adjustable beam lock for looms comprising a body section, a bearing section pivotally mounted in and between the walls of the body section, oppositely disposed hubs projecting from the sides of said body section, either of said 110 hubs being adapted to co-operate with a recess in one of the side frames of the loom, means carried by the body section for adjusting and retaining in adjusted position the bearing section with respect to the body section, the said body section being provided with a transverse aperture through which 115 securing means may be passed.

6. A symmetrical adjustable beam lock for looms comprising a body section, a bearing section pivotally mounted in and between the walls of the body section, oppositely disposed hubs projecting from the sides of said body section, either of said 120 hubs being adapted to co-operate with a recess in one of the side frames of the loom, a 125

set screw threaded into the body section and abutting the bearing section whereby the bearing section may be adjusted with respect to the body section, the said body section being provided with a transverse aperture through which securing means may be passed.

In testimony whereof, we have signed our names to this specification.

JOSEPH EMILE TÉTU.
EMMA E. CUTLER,
